UNITED STATES PATENT OFFICE.

OLIVER N. PLANTE, OF LOWVILLE, NEW YORK.

COMBINATION-TOOL.

1,141,141.

Specification of Letters Patent.

Patented June 1, 1915.

Application filed February 4, 1915. Serial No. 6,045.

To all whom it may concern:

Be it known that I, OLIVER N. PLANTE, a citizen of the United States, residing at Lowville, in the county of Lewis and State of New York, have invented certain new and useful Improvements in Combination-Tools; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in compound tools and especially in the provision of a tool having a handle to which is fixed a can opening blade, the shank portion of which serves as a spring for holding tools carried by the handle in different positions for use and non-use.

The present invention comprises various details of construction, combinations and arrangements of parts which will be herein-after fully described, shown in the accompanying drawings and then specifically defined in the appended claims.

I illustrate my invention in the accompanying drawings, in which:—

Figure 1 is a side elevation showing the tools folded. Fig. 2 is a similar view of the reverse side of the device. Fig. 3 is a sectional view on line 3—3 of Fig. 1. Fig. 4 is a sectional view on line 4—4 of Fig. 1. Fig. 5 is a detail perspective view of a part of the invention, and Fig. 6 is a detail view in elevation of the can opener end of the tool.

Reference now being had to the details of the drawings by letter, A designates a handle, made preferably of a strap of metal of any suitable shape, preferably as shown in the drawings, and B is a can opening blade which is riveted to one end of the holder and has a beveled cutting edge B' and a laterally extending portion B² forming a means for removing a cap from a bottle. The rear end, designated by letter B² of the can opener, is resilient and engages shoulders F² and I formed respectively on the bosses F' and H' which are journaled upon the pin E. The boss F' has an integral tack claw F and the boss H' an integral screw driver H, said resilient end B² of the can opener serving to hold said tack claw and screw driver folded in the shape shown

in Figs. 1 and 2 of the drawings when not in use.

Pivots mounted upon the pin E is a cork screw N having two notches O and P respectively therein and designed to be engaged by the resilient end B² of the can opener and is provided also with a cam projection R, serving as a means, when coming in contact with the resilient end of the can opener, to cause the same to be thrown out of the notch to allow the cork screw to turn upon its pivot. It will be noted upon reference to Fig. 4 that the cork screw is held in a closed relation between the sides of the handle by the adjacent end of the can opener engaging the notch O and, when the cork screw is open, the adjacent end of the cork screw will engage the notch P.

Upon reference to Fig. 3 of the drawings, showing the reverse side of the tool from that shown in Fig. 1, it will be noted that a notch or shoulder F³ is formed in the boss F' which is engaged by the resilient end B² of the can opener to lock and hold the tack claw open for use and that a similar notch K, shown in Fig. 2, is formed in the boss of the screw driver H and serves as means for receiving the resilient end of the can opener to hold the screw driver open or in the position shown in Fig. 1 of the drawings.

Upon reference to Fig. 6 of the drawings, it will be noted that a recess B⁴ is formed in a projection integral with one end of the handle and the end of said projection is inclined as at B³ and serves as a means to engage the edge of a can while being opened by the cutting blade.

Upon reference to Fig. 2 of the drawings, it will be noted that one edge of the handle is recessed, the ends of the recesses terminating in shoulders A' and A² upon one side, and A³ and A⁴ upon the other side of the longitudinal center, said recesses being adapted to receive respectively the screw driver and the tack claw when thrown to positions shown in dotted lines to brace the same against lateral movement, while the bosses which are integral with the tools are securely held by the resilient end of the can opener.

In operation, when it is desired to use either the screw driver or the tack claw, either may be swung out to the position shown in dotted lines in Figs. 1 and 2, the resilient end of the can opener yielding to allow the tools to swing and holding the

same in their adjusted positions. A swinging movement of the cork screw may also be effected to cause the same to be held either in a closed or in an operative position, the cam upon the cork screw serving to throw the resilient end of the can opener out of the notches. When the tools within the handle are not in use, they will be held by the resilient end of the can opener in the 10 space between the sides of the handle.

What I claim to be new is:—

1. In combination with a handle made up of a strap of iron bent in oblong form and having a solid projecting portion at one end 15 thereof, said handle having a recess in the edge thereof and the projection provided with a shoulder forming one wall of the recess, a pin mounted in the opposite walls of the handle, a tool having a boss at its inner 20 end pivotally mounted upon said pin and adapted to swing into said recess and engage the shoulder formed upon said projection, and means for holding the tool in said recess.
- 25 2. In combination with a handle made up of a strap of iron bent in oblong form and having a solid projecting portion at one end thereof, said handle having a recess in the edge thereof and the projection provided 30 with a shoulder forming one wall of the recess, a resilient member fastened to said projection, a pin mounted in the opposite walls of the handle, a tool having a boss at its

inner end pivotally mounted upon said pin and adapted to swing into said recess and 35 engage the shoulder formed upon said projection, the inner end of said resilient member being adapted to engage the shoulder of the boss to hold the tool in said recess.

3. In combination with a handle made up 40 of a strap of iron bent in oblong form and having a solid projecting portion at one end thereof, said handle having a recess in the edge thereof and the projection provided with shoulders forming walls coöoperating 45 with the recess, a resilient member fastened to said projection, a pin mounted in the opposite walls of the handle, carrying tools each having a boss at its inner end pivotally mounted upon said pin and adapted to swing 50 into said recess and engage the shoulder formed upon said projection, the inner end of said resilient member being adapted to engage the shoulder of the boss to hold the tool in said recess, and means upon said 55 pin for throwing the resilient end of said member out of said notch when it is desired to swing the tools into the space between the walls of the handle.

In testimony whereof I hereunto affix my 60 signature in the presence of two witnesses.

OLIVER N. PLANTE.
